United States Patent Office.

THOMAS B. STOUT, OF KEYPORT, NEW JERSEY.

Letters Patent No. 91,179, dated June 8, 1869.

IMPROVED CARPET-STRETCHER..

The Schedule referred to in these Letters Patent and making part of the same.

To all whom it may concern:

Be it known that I, THOMAS B. STOUT, of Keypoint, in the county of Monmouth, and State of New Jersey, have invented an Improved Carpet-Stretcher; and I do hereby declare that the following is a full and exact description thereof, reference being had to the accompanying drawings, making part of this specification—

Figure 1 being a side view of the instrument, showing its position when in the ordinary act of using it.

Figure 2, a corresponding view, showing its position when the carpet is stretched into place, and secured there by the instrument.

Figure 3, a bottom view of the instrument.

Like letters designate corresponding parts in all of the figures.

This instrument consists essentially of a handle, A, a fulcrum or upright, B, a stretcher-claw, C, and a holding-spur or dog, D.

The claw C is formed with or secured firmly to a shank, a, which is inserted into the handle A, or the claw may form an extension of the handle itself.

The fulcrum B is pivoted at b, to the claw c, in a proper position, substantially as shown.

The lower edge of the fulcrum may be continuous, and quite thin, so as to fit closely in the corner of a room, where the floor and base-board meet as indicated in fig. 2.

It is kept separated from the claw by a slight spring, f, (fig. 3,) when not brought into use.

The claw C, has teeth c, for catching hold of the carpet, as usual.

The holding-dog D is inserted in or secured to the handle A, just forward of where the hand grasps the handle. It consists of a spur with a sharp point, which can be readily forced into the floor, when required to hold the carpet in place. It may have a brace, d, extending forward to the handle, as indicated in the drawings.

In using my improved carpet-stretcher, the fulcrum B is ordinarily kept, by the spring f, out of the way of the claw C, as indicated in fig. 1.

Thus the carpet can be stretched either by engaging the claw C into the edge, or any part of the middle of a carpet-breadth, over any part of the floor, exactly as an ordinary carpet-stretcher is used, no attention

being given to the fulcrum. But when, at any time, additional power is wanted, the handle is raised till the lower edge or end of the fulcrum rests on the floor, and then, by thus bringing the powerful leverage produced in working on the fulcrum, into operation, the carpet is easily forced along.

This act of using the fulcrum causes the claw C to raise the carpet from the floor, so that a great amount of friction is taken away, and the work is performed with half the labor that would be required to stretch the carpet, while forcibly pressed down upon the floor, as in ordinary carpet-stretching. This is a very important advantage of the fulcrum.

Then, when the edge of the carpet approaches the base-board, the fulcrum first strikes it, and is thus automatically brought into action, and on bringing the claw up to it, the carpet at that point is finally brought into place, ready for fastening.

By continuing to lower the handle at that final movement, the pointed dog D is forced down into the floor, and holds the carpet in place till it is nailed down, or otherwise fastened there.

Thus it is seen that the fulcrum B produces two very important advantages first, raising the carpet from the floor and thereby diminishing friction; second, bringing the claw with the edge of the carpet, exactly into place.

Any unessential variation of the construction may be adopted if desired.

What I claim as my invention, and desire to secure by Letters Patent, is—

The fulcrum B, arranged and operating, in combination with the claw C of a carpet-stretcher, substantially as and for the purpose herein specified.

Also, the dog D, attached to the handle A, and operating in combination with the claw C, pivoted upon the fulcrum B, substantially as and for the purpose herein set forth.

The above specification of my improved carpet-stretcher signed by me, this 16th day of June, 1868.

THOS. B. STOUT.
